(57) **CLAIM**

The ornamental design for a lubrication shield for directing the application and dispersement of lubricants, cleaners and dressings to chains, cables, ropes and lines, as shown.

DESCRIPTION

FIG. 1 is a front perspective view of a lubrication shield for directing the application and dispersement of lubricants, cleaners and dressings to chains, cables, ropes and lines showing my new design;

FIG. 2 is a rear perspective view thereof;

FIG. 3 is a top view thereof;

FIG. 4 is a front view thereof;

FIG. 5 is a bottom view thereof;

FIG. 6 is a rear view thereof;

FIG. 7 is a right view thereof; and,

FIG. 8 is a left view thereof.

Any broken lines present are indicative of environmental structure in the drawing and are not part of the design sought to be patented.
